UNITED STATES PATENT OFFICE

JOSEF SCHAEFER, OF DORTMUND, GERMANY

REGENERATIVE COKE OVEN

Application filed October 26, 1929, Serial No. 402,655, and in Germany December 27, 1928.

This invention relates to regenerative coke ovens and has more particularly reference to the means for reversing at determined intervals the flow of the heating gases in ovens of this class, the object of this reversal being to alternately preheat during a determined period of time the fuel gas by one group of regenerators and to reheat another group thereof during this time by the escaping waste gases, whereupon, inversely, these latter regenerators preheat the fuel gas while the first-named group is reheated again by the escaping waste gases. In coke ovens of this class three way cocks are made use of among others for feeding the heating gases to the flues to be fired which cocks on the one hand are connected to the gas main and on the other hand by two sockets to two gas branches one of which leads to the one group of heating flues and the other to the other group thereof.

Now in a heating arrangement of this design it is of advantage to prevent the heating gas when shut off from the one group of heating flues by these three way cocks, from at once entering the other group of flues, because these latter are still full of waste gases which have to be blown out therefrom before the heating gas can be ignited therein and heat them. This desired interruption in the reversal of the gas flow from one group of heating flues to the other can be realized in a very simple manner by using three way cocks the plug of which when thrown over keeps closed during a short period of time the two branch conduits so that in the reversal of the gas flow first the air of combustion enters the heating flues to be flamed anew, and it is this air which drives out the waste gases therefrom, whereupon only then the heating gas enters and combustion takes place so that no heating gas is mixed uselessly with the waste gases.

Now according to the invention this gas flow reversing arrangement is improved by the plug of the three way cocks being provided with a supplementary passage by which air is fed to the one or better to both of the two branch conduits during that period of time where they are out of connection with the gas

main. In entering the oven from the branch conduits this air causes eventual deposits in the gas distributing passages and burners of the oven and eventually also in the heating flues to burn away. Another advantage afforded by driving air through the gas branch conduits leading to the heating flues while the gas is shut off from both groups of flues consists in the fact that any pressure below atmospheric pressure is avoided within the heating flues which phenomenon is to be observed in the reversal of flow otherwise during the time the flues are out of communication with the gas supply, and causes distillation gases to pass from the oven chambers through eventual leaky walls to the heating flues.

In order that the invention can be more easily understood, a reversal arrangement comprising three-way cocks according to the invention is illustrated by way of example in the accompanying drawing in which

Figure 1 is a sectional view of an individual three-way cock in connection with the gas main and the gas branch conduits,

Figure 2 is a similar view with the plug of the cock in another position,

Figure 3 is a longitudinal section through the cock, and

Figure 4 shows the general arrangement of the gas reversal means on a battery of coke ovens.

Referring to the drawing *a* denotes the gas main from which the heated gas to be ignited is fed to the heating flues of the coke oven chambers, *h* denotes the three-way cocks attached to the gas main *a*, while *k* denotes the plug of these cocks *h* which is fitted with an angular bore *i*. *b* and *c* denote the branch conduits leading from each three-way cock *h* to the groups of heating flues *d* and alternatively feeding the gas to the group to be fired.

As to be seen best from Figure 2, the plug bore *i* is so dimensioned and the angle included on the cock by the branch conduits *b*, *c*, is so wide that with the bore *i* in an intermediate position between the branches *b* and *c* the plug *k* closes these branches.

Now the plug *k* is fitted on each side of the

- bore *i* with passages *j* which connect the two branches *b*, *c* with an air inlet, that is, with the outer air in that position of the plug, Figure 2, in which the branches *b*, *c*, do not communicate with the plug bore *i*. In this position of plug bore *i* in which the gas main *a* is thus shut off from the branches *b*, *c*, air is supplied in a suitable quantity to branches *b*, *c* through the passages *j* and through these branches to 10 the gas distributing channels of the oven and to the burners arranged in the heating flues, and to the latter themselves and burns away eventual deposits therein before the normal heating of and, the escape of the waste 15 gases from, the heating flues commences.

What I claim and desire to secure by Letters Patent is:—

1. In a regenerative coke oven heating flue system, the combination with the heating flues 20 adapted to be fired alternately, of a gas main, branch pipes leading from the gas main to the heating flues, a three-way valve inserted between the gas main and branch conduits for controlling the admitting of the 25 gas from the gas main alternately to one or other heating flues through its branch conduit, and means incorporated in the valve for admitting air to a heating flue through its branch conduit prior to the admission of gas 30 thereto for expelling the previously combusted gas in such heating flue.
2. In a regenerative coke oven heating flue system, a three-way valve having its two outlets connected respectively to the flues and its 35 inlet connected to the source of gas supply and including a rotatable plug having a passage therein for establishing communication between the inlet and the outlets alternatively, said plug having a supplemental passage for 40 supplying fresh air alternatively to the heating flues upon the plug closing communication between the inlet and the alternative outlets.
